UNITED STATES PATENT OFFICE.

WINFRED MUDGE BROOKS, OF SOUTH ORANGE, NEW JERSEY.

SEALING MEANS.

1,416,683.

Specification of Letters Patent. Patented May 23, 1922.

Application filed September 24, 1921. Serial No. 502,963.

To all whom it may concern:

Be it known that I, WINFRED M. BROOKS, a citizen of the United States, and a resident of South Orange, in the county of Essex and State of New Jersey, have invented 5 certain new and useful Improvements in Sealing Means, of which the following is a specification.

This invention relates to sealing devices 10 of the character in which a tell-tale member is bent back upon itself or upon another member, the bending taking place in the plane of a weakened zone so that when said tell-tale member is unbent the metal is fractured and the member detached thereby thus revealing that the seal has been tampered with.

The weakened zone has heretofore been 20 produced by scoring or grooving the material, the groove being of equal depth throughout its length, and with this construction difficulty has been experienced in obtaining requisite degree of weakness without, at the same time, rendering the material so weak 25 as to fracture the material during the locking and sealing operation.

I have found that by varying the depth 30 of the groove longitudinally with its deepest part at its center portion and shallowest parts at its ends, the integrity of the material of the tell-tale member is assured when the member is bent during the sealing or locking operation and, at the same time, fracture of the material when unbending the 35 same is invariably effected.

In the accompanying drawings the invention is disclosed in a concrete and several preferred forms in which—

Fig. 1 is a plan view of a sealing member 40 embodying the invention;

Fig. 2 is a plain view of a modified form of sealing member embodying the invention;

Fig. 3 is a detail plan view of the weakened zone;

Fig. 4 is a longitudinal sectional view 45 through one of the grooves;

Fig. 5 is a transverse sectional view through the weakened zone.

The character of the sealing medium is immaterial and I have shown, in Fig. 1 as an 50 illustration of the use to which the invention may be put, the type of sealing medium disclosed in Patents Nos. 1354164 and 1380038 and, in Fig. 2, the character of the sealing medium disclosed in application Ser. No. 55 490213 and it is therefore unnecessary to describe the construction and operation of these devices in detail except to state that 1 is a tell-tale member which may be integral with a main member 2 or separate therefrom and 60 is provided with a weakened zone produced by one or more grooves 3.

The groove, as here shown, has a curved bottom the curve being longitudinal of the groove and deepest at its center part 4 and 65 shallowest at its ends 5. It will also be noted that said groove is also wider at its central portion than at its end portions.

I claim:

1. In a sealing device, a tell-tale member 70 having a weakened zone, the weakening consisting of a groove of varying depth longitudinally with its deepest part at the center portion and shallow parts at its ends.

2. In a sealing device, a tell-tale member 75 having a weakened zone, the weakening consisting of a groove, the bottom of which is curved longitudinally with its deepest part at its center portion and shallow parts at its ends.

Signed at New York city, in the borough of Manhattan, county and State of New York, this 22nd day of September, 1921.

WINFRED MUDGE BROOKS.
